UNITED STATES PATENT OFFICE.

THADDEUS C. JOY, OF TITUSVILLE, PENNSYLVANIA.

STEAM-GENERATOR.

SPECIFICATION forming part of Letters Patent No. 269,582, dated December 26, 1882.

Application filed July 12, 1882. (No model.)

To all whom it may concern:

Be it known that I, THADDEUS C. JOY, a citizen of the United States, residing at Titusville, in the county of Crawford and State of Pennsylvania, have invented a new and useful Steam-Generator, of which the following is a specification.

My invention relates specially to improvements in the steam-generators shown in Letters Patent to me, numbered 209,895, 233,624, and 258,075, such generators comprising a water-tank, heating-sections, and steam-drum sections, which parts or sections are united by screw-bolts and flanges or other suitable means, and are made to communicate with one another by pipes; and the object of my improvement is to so construct steam-generators of this class that they may be readily taken apart and put together, and by using more or less of the respective sectional parts the generators may be made longer or shorter to suit different purposes.

My present invention will be clearly understood from the following specification, claims, and the accompanying drawings, in which latter—

Figure 1 is a top view of my improved steam-generator. Fig. 2 is a horizontal section of the same below the steam-drums. Fig. 3 is a vertical central longitudinal section of the generator. Fig. 4 is a perspective view of one of the heating-sections and steam-drums. Fig. 5 is an elevation of two such heating-sections and steam-drums placed opposite each other, as they are used in practice. Fig. 6 is an elevation of the two above-mentioned heating-sections and steam-drums as they appear when united in one piece. Fig. 7 is an elevation of a heater having a downward-extended steam-drum.

Similar letters refer to similar parts throughout the several views.

The steam-generator A is composed in the main of two water-tanks, B, a number of heating-sections, C, V-shaped water-chambers D, and steam-drum projections E.

The water-tanks B may be of any suitable form; but their inward sides are straight by preference.

The heating-sections C are of oblong form, with

guttered sides, as at c, which match, so that two of such heating-sections, when united, will form a vertical passage, c'. These heating-sections have parallel sides, and are arranged in two parallel rows between the ends of the water-tanks, 55 as shown, and they are connected to the end of the water-tanks, the connections being effected by means of lugs c² and bolts c³, or in any other suitable way. The heating-sections C have upper and lower communications with each other and with the water-tanks, as at c⁴. These communications are made water and steam tight by planing or otherwise preparing the surfaces surrounding the communicating apertures, so that with the aid of packing material—such as asbestos—a perfect joint will be secured. Short connecting-pipes, suitably fastened between and to the heating-sections and the water-tanks, will serve the same purpose as the hereinbefore-described connections 70 without changing the principle of my invention.

To each heating-section C a V-shaped water-chamber, D, is attached by means of communicating pipes d at the top and at the bottom, so as to afford steam and water communications. Upon each heating-section a steam-drum, E, is formed. The drums E have inclined sides e', which inclose spaces coinciding with the openings or passages c' in the heating-sections below, and thus conduct the draft 80 over the V-shaped water-chambers D. The tops e² of the steam-drums E are rectangular and join each other as well as the tops of the tanks B, so as to present together a flush top surface.

An outlet, b, may be provided for the smoke, either through one of the tanks B or any other suitable part of the steam-generator.

The above-described steam-generator may be placed upon a fire-pot of suitable construction, or such fire-pot may be omitted, and the heating-sections C may be sufficiently lengthened to form a fire-chamber below the V-shaped water-chambers D.

The water-chambers D may be united in one 95 piece with the steam-drums E, as shown in Fig. 7, and may be either V-shaped or of other suitable form.

Two heating-sections C, having steam-drums E, may be united, as seen in Fig. 6; or 100

a heating-section C may be provided with an extended steam-drum, E, as seen in Fig. 7, and the V-shaped water-chamber may be omitted.

5 These modifications in the arrangement and construction of the heating-sections, V-shaped water-chambers, and steam-drums may be adopted without altering the principle of my invention.

10 What I claim as my invention, and desire to secure by Letters Patent, is—

1. In a steam-generator, A, the combination of the heating-sections C, water-chambers D, with steam-drums E, arranged in two

15 parallel opposite rows, and two transverse water-tanks arranged at the ends thereof, substantially as and for the purpose described.

2. In a steam-generator, A, the water-tanks

B and heating-sections C, having guttered sides and arranged between them, and having 20 communicating passages *c*⁴, substantially as described.

3. In a steam-generator, A, the heating-sections C, having guttered sides, and with projecting parts E, arranged in two parallel lines, 25 and having communicating passages *e*, substantially as described.

4. In a steam-generator, A, the heating-sections C, having guttered sides, and water-chambers D, arranged in two parallel lines, 30 and having communicating passages *d*, substantially as described.

THADDEUS C. JOY.
